UNITED STATES PATENT OFFICE.

EARL A. WHEELER, OF BAKERSFIELD, CALIFORNIA.

ROAD PLANER AND GRADER.

Application filed December 3, 1921. Serial No. 519,704.

To all whom it may concern:

Be it known that I, EARL A. WHEELER, a citizen of the United States, residing at Bakersfield, in the county of Kern and State 5 of California, have invented new and useful Improvements in Road Planers and Graders, of which the following is a specification.

My invention relates to a road planer and grader, the principal objects of my invention being to generally improve upon and simplify the construction of the existing types of similar machines, to provide a machine that may be easily and economically 10 operated and which will be effective in cutting off and leveling irregularities in the surfaces of roadways, and further to provide a road grading and leveling machine having a wide range of adjustability so as 15 to materially increase its scope of usefulness.

Further objects of my invention are to provide a machine that will render the surface of the road smooth and level without 20 in any way affecting or injuring the base or foundation of the roadway, and further to provide a construction having a plurality of ground engaging members that are constructed and arranged so as to co-operate in 25 very rapidly and efficiently producing relatively smooth level surfaces on roadways, and further to provide a machine having means preferably in the form of runners that are normally positioned out of contact with the surface of the ground, and which, under certain conditions, are adapted 30 to rest on the surface of the ground to limit the movement of certain parts of the machine below the surface of the roadway 35 that is being acted upon.

With the foregoing and other objects in view, my invention consists in certain novel features of construction and arrangement of parts that will be hereinafter more fully 40 described and claimed and illustrated in the accompanying drawings, in which:

Figure 1 is a top plan view of a road planer and grader of my improved construction.

Fig. 2 is a side elevational view of the 50 machine.

Fig. 3 is a vertical section taken approximately on the line 3—3 of Fig. 1.

Fig. 4 is a cross section taken approximately on the line 4—4 of Fig. 2. 55

Fig. 5 is a cross section taken approximately on the line 5—5 of Fig. 2.

Fig. 6 is a cross section taken approximately on the line 6—6 of Fig. 2.

Fig. 7 is an enlarged detail section taken 60 approximately on the line 7—7 of Fig. 4.

Fig. 8 is a plan view of the vertically adjustable member of the machine that carries the two sets of road surface engaging teeth or scarifiers. 65

Fig. 9 is a cross section taken approximately on the line 9—9 of Fig. 2.

Fig. 10 is a vertical section taken approximately on the line 10—10 of Fig. 8.

Fig. 11 is a cross section taken on the 70 line 11—11 of Fig. 2.

The main body or quadrangular frame of my improved planer or grader comprises a pair of elongated runners 10 that are preferably formed of suitable timbers that are 75 spaced a suitable distance apart and which are framed together by suitable transversely disposed members 11. The lower forward corners of the beams forming these runners are cut away and rounded as designated by 12, and applied to said rounded corners and the lower edges of the beams are flat metal straps 13. Secured to the forward end of each runner 10 is a forwardly projecting loop 14, and these loops provide points of attachment for the chains or cables that are utilized in drawing the machine over the surface of a roadway. Secured to the forward portions of the runners 10 and upon the inner faces thereof 80 are vertically disposed channels 15 in which are arranged for sliding movement the vertically disposed members 16 of a substantially rectangular frame 17.

Swiveled to the upper portion of frame 95 17 are the upper ends of inverted U-shaped yokes 18, and journaled in each yoke is a relatively small traction wheel 19 that is

provided with a broad bearing face. Secured to the upper ends of the channels 15 is a transversely disposed bar 20 that serves as a support for the upper portions of rotatably mounted rods 21, each of which is provided on its upper end with a hand wheel 22. The lower portions of the rods 21 are threaded as designated by 23, and said threaded portions are screw seated in blocks 24 that are secured to the lower portion of frame 17. The construction just described provides means for raising or lowering the wheels 19 that provide a rolling support for the forward end of the machine. The yokes 18 are curved slightly to the rear so that the wheels 19 may perform the functions of caster wheels while the machine is in operation.

The rear portion of the machine is supported by one or more relatively broad faced wheels 25 that is journaled on a shaft 26, and the latter being secured in the lower portion of a substantially rectangular frame 27 that is arranged to slide vertically between channels 28 that are secured to the inner faces of the rear portions of runners 10. Frame 27 and the wheels 25 may be adjusted vertically by the manipulation of vertically disposed rods 29 carrying at their upper ends hand wheels 30, and the lower ends of said rods being threaded as designated by 31, and which threaded ends pass through blocks 32 that are carried by the lower portion of frame 27. The parts just described provide an adjustable rolling support in the rear portion of the machine; means for adjustment of the respective rolling supports of the main frame being provided, as described, in the form of a screw near each corner thereof.

Arranged on the inner faces of the members 10 a short distance to the rear of the guiding channels 15 are vertically disposed pairs of guide members 33 between which are arranged the ends of a vertically movable block 34, and extending vertically through suitably formed openings in the end portions thereof are rods 35, each of which is provided on its upper end with a hand wheel 36. The lower portions of these rods 35 are screw threaded, and said threaded portions are screw seated in blocks 37 that are arranged in the end portions of the block 34, and which arrangement provides simple and efficient means for raising and lowering said block 34 and adjusting its vertical position with respect to the surface of the roadway.

Formed directly in the front face of block 34 is a series of vertically disposed continuous grooves 38 in each of which is arranged a bar 39, and the lower portions of all of the bars being curved forwardly a slight distance. Extending transversely across the front face of block 34 adjacent to its upper

and lower edges are bars 40, the ends of which are secured to said block 34 in any suitable manner, and seated in said bars are set screws 41, the inner ends of which engage directly against the front faces of the bars 39, thereby providing means for firmly locking said bars 39 to the block 34 and maintaining said bars in their vertically adjusted positions. The extreme lower ends of the bars 39 are cut off at right angles so as to provide said bars with blunt rounded engaging ends.

Formed in the rear face of block 34 is a series of vertically disposed grooves 42 in each of which is positioned a vertically disposed bar 43, and the lower ends of these bars are curved forwardly and tapered so as to provide pointed ground engaging lower ends 44. Transversely disposed bars 45 have their ends secured to block 34, and passing through said bars 45 are set screws 46 that engage the bars 43 and lock the same to block 34 in their vertically adjusted positions.

Arranged on the inner faces of members 10 a short distance to the rear of the guideways 33 are vertically disposed channels 47, the upper ends of which are connected by a cross bar 48, and arranged to move vertically through said channels are the vertically disposed members of an inverted U-shaped frame 49. This frame and the parts carried thereby are moved vertically by means of rods 50 that are journaled in cross bar 48, the upper ends of said rods being provided with hand wheels 51, and their lower portions being threaded and engaging in the cross bar at the top of frame 49. Carried by the lower portion of frame 39 is a horizontally disposed rod or shaft 52, and loosely arranged thereupon is a series of relatively wide discs 53 of uniform size and shape and which are adapted to serve as clod crushers or pulverizers while the machine is in operation.

Arranged on the inner faces of the members 10 to the rear of the frame 49 that carries the rollers 53, are pairs of vertically disposed guiding members 54, the same being inclined with respect to the planes occupied by the inner faces of said members 10, and one pair of said guideways being offset with respect to the other set.

Arranged to slide vertically between these pairs of inclined guideways is an inclined block 55 provided on its front face with a metal plate 56, and said block and plate being cut away at the lower rear corner to provide an opening 57 through which excess dirt or gravel may pass while the apparatus is in operation.

Disposed above the guideways 56 is an inverted U-shaped frame 58 that serves as a support for the upper portions of rods 59, the upper ends of the latter being provided with hand wheels 60, and the lower portions

of said rods extending downwardly through openings 55' that are formed in block 56. The lower portions of the rods 59 are threaded, and said threaded portions engage in blocks 61 that are seated in the block 56, such construction providing means for raising and lowering the block 55 that carries the scraping member 56.

In the use of my improved road grading and leveling machine, the supporting rollers 19 and 25 are adjusted vertically by proper manipulation of the rods 21 and 29 so that the members 10 occupy positions with their under faces slightly elevated with respect to the surface of the roadway.

The machine is drawn forwardly by a tractor or other suitable motive power, and block 34 carrying the bars 39 and 44 is adjusted vertically so that the lower ends of said bars engage the surface of the roadway and scarify or cut into the same to a slight depth. As the machine moves forward, the rollers 53 crush and pulverize the clods or pieces of dirt thrown up by the scarifying members, and the lower edge of the plate 56 passes over the surface of the roadway immediately to the rear of the rollers 53, thereby cutting off and leveling all irregularities and producing a relatively smooth surface. Any excess of dirt or gravel that is cut away by the plate 56 will pass rearwardly along the inclined front face of said plate and finally discharge through the opening 57 at the end thereof. The rotary crushing members 53 are raised or lowered by proper manipulation of the rods 50, and the block 55 carrying the scraper member 56 may be raised or lowered by proper manipulation of rods 59.

It will be understood that under normal conditions or while the machine is in service the entire weight of the machine is carried by the wheels 19 and 25, which have relatively wide rims or ground engaging faces, and that said wheels may be readily adjusted so that the parts 39 and 43 may penetrate the surface of the roadway to any desired depth. If the wheels pass into a rut or depression in the surface of the roadway, the lower faces of the runners 10 will engage the surface of the roadway, thereby limiting the downward movement of the scarifying bars 39 and 43, until the wheels pass out of the rut or depression. Thus the construction of my improved machine is such that the scarifying members are prevented from passing downwardly into the base of the roadway and tearing up or destroying the same.

Further, the construction of my improved machine is such that the scarifying members 39 and 43 may be subjected to practically two-thirds of the weight of the entire machine, and as a result such scarifiers will penetrate the harder portions of the surface

of the roadway and readily break up the same, and which surfaces are afterwards finished or smoothed off by the scraper member 56. The bars or scarifying members 39 and 43 are independently mounted so that any one or all of said bars may be adjusted vertically so as to operate to best advantage during the movement of the machine over the roadway.

The bars 39 and 43 are offset or staggered with relation to each other so that the lower ends thereof engage and scarify all portions of the surface of the roadway over which the machine is drawn.

The adjustability of the various parts of the machine that engage the surface of the roadway adds materially to the effectiveness of the machine.

Thus it will be seen that I have produced a road leveling and grading machine that is of relatively simple structure, capable of being easily drawn over the surface of the roadway, and said machine being equipped with readily adjustable parts that are effective in rendering the surface of the roadway smooth and level without affecting the base or foundation of said roadway.

It will be understood that minor changes in size, form and construction of the various parts of my improved road planer and grader may be made and substituted for those herein shown and described without departing from the spirit of my invention, the scope of which is set forth in the appended claims.

I claim as my invention:

1. In a road planer and grader, a frame including a pair of runners, vertically adjustable rolling supports therefor, adjusting means therefor near each of the four corners of said frame, vertically adjustable scarifying members carried by said frame, a series of rotary crushing members adjustably arranged in the frame, and a vertically adjustable scraper arranged in the rear portion of the frame.

2. In a road planer and grader, a mobile frame, a block arranged for vertical adjustment on said frame, said block being provided in one of its faces with a series of vertically disposed parallel grooves in the form of continuous channels cut in said block, and scarifying members adjustably seated in said grooves.

3. In a road planer and grader, a mobile frame, a block arranged for vertical adjustment on said frame, said block being provided in one of its faces with a series of vertically disposed parallel grooves in the form of continuous channels cut in said block, scarifying members adjustably seated in said grooves, and an adjustable scraper arranged in the rear portion of said mobile frame.

4. In a road planer and grader, a mobile frame, a block arranged for vertical adjust-

ment on said frame, said block being provided in one of its faces with a series of vertically disposed parallel grooves in the form of continuous channels cut in said block,
5 scarifying members adjustably seated in said grooves, an adjustable scraper arranged in the rear portion of said mobile frame, and

a vertically adjustable series of crushing rollers arranged for operation in the frame in front of the scraper.

In testimony whereof I have signed my name to this specification.

E. A. WHEELER.
